UNITED STATES PATENT OFFICE.

REGINALD A. FESSENDEN, OF WASHINGTON, DISTRICT OF COLUMBIA, ASSIGNOR, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

TRANSMITTING AND RECEIVING SIGNALS.

1,157,094.

Specification of Letters Patent.

Patented Oct. 19, 1915.

Original application filed June 2, 1900, Serial No. 18,878. Divided and application filed March 29, 1901, Serial No. 53,441. Divided and this application filed May 4, 1904, Serial No. 206,392. Renewed September 10, 1915. Serial No. 50,106.

To all whom it may concern:

Be it known that I, REGINALD A. FESSENDEN, a citizen of the United States, residing at Washington, in the District of Columbia, have invented certain new and useful Improvements in Transmitting and Receiving Signals, of which the following is a specification.

The invention described herein relates to certain improvements in the transmission and receipt of electromagnetic waves or impulses particularly for signaling by wireless telegraphy.

The present invention has for its object the practical transmission and receipt of impulses representing signals or messages without mutual interference of the two operations, and also the transmission and receipt of independent signal elements during the same time.

The invention is hereinafter more fully described and claimed.

In the accompanying drawings forming a part of this specification I have shown partly in diagram apparatus for carrying out my invention.

In the practice of my invention a vertical generating wire or generating surface, 5^a, is connected at the sending station according to the so-called "impulsive" type of connection to a terminal or knob 4^a of an induction coil 1^a. The secondary coil is connected as usual to both discharge terminals of the induction coil and also to ground. The primary of the induction coil is included in the circuit of a generator 2 and in said circuit is included a circuit make and break mechanism. A convenient form of make and break mechanism consists of a metal disk 3^a mounted upon a shaft 20 and electrically connected therewith. The shaft is connected to one pole of the generator 2. The disk 3^a is provided with a shoulder 22 adapted when the disk is rotated to strike against the plate 23^a connected to the opposite pole of the generator 2. The disk 3^a is adjustably held in position on the shaft and may be clamped in any desired position.

By rotation of the shaft the circuit of the generator will be made and broken at each rotation. As the periodicity of the magnetic waves is dependent upon the self-induction

multiplied by the capacity and as self-induction and capacity of the sending wire vary with the length and the diameter of the wire, the latter is so proportioned, as by varying its length as to give the desired periodicity.

The receiver at the distant station is essentially like the transmitter and its receiving wire is adjusted to have substantially the same periodicity as the sending wire—i. e., the wire or generating surface at the receiving station and the corresponding wire at the sending station have the same value of the quantity self-induction multiplied by the capacity. The tuning of this pair of wires may be done conveniently by slightly varying the length or diameter of one of them. The mechanism controlled or operated by the voltages or current induced in the receiving wire is preferably so tuned in accordance with practices and rules well known in the art, that the recording or indicating mechanism connected to the receiving wire will be acted on or operated only by the voltages or currents induced by the magnetic waves from the corresponding wire at the sending station. As for example, the indicating mechanism connected to the receiving wire 5^a will not be acted on or operated by any voltages or current other than that induced by magnetic waves generated by the sending wire 5^a.

Any suitable form or construction of mechanism may be employed for recording or indicating the signals received. As for example, the coherer 24^a arranged in the circuit of the grounded receiving wire. This coherer is also included as is customary in circuit 25^a from a generator 26, said circuit also including portions of the recording or indicating mechanism 33^a. The recording mechanism or other indicator may be of any preferred type.

In lieu of a coherer, mechanism may be employed for transforming the current or voltages induced by the magnetic waves into energy of motion as shown and described in Patent Number 706,735. This mechanism is a current operated, low resistance, cumulatively acting, constantly receptive, receiver adapted to transform the energy of the received electromagnetic waves directly into

the energy of motion. In the drawing is shown a form of such mechanism, which consists of a coil 7^a in series with the receiving wire 5^a and a ring or element 8 so supported in the coil that a plane at right angles to the axis of the ring or element will be at an angle of approximately 45° with a plane at right angles to the axis of the coil. This ring is balanced on knife edges or supporting rods 13, 13^a, one of which is formed of a good electrical conductor, as silver, the ring or element being preferably formed of aluminum, silver, or other good conductor. A carbon block 14 is so arranged that a portion of the ring will normally rest lightly thereon. This microphonic contact, the element 8 and the conducting pivotal support 13 for the latter, form parts of a circuit from a generator 15. The indicating mechanism may be directly or indirectly controlled by the circuit of generator 15.

As the wire or surface 5^a at one station may be employed both for generating and receiving the magnetic waves, as signals are sent or received, the indicating or receiving mechanism and the generating mechanism are connected to said wire or surface as shown in the drawing. In order to protect the indicating or receiving mechanism when sending messages, a switch mechanism is interposed between the wire or surface 5^a and said indicating mechanism. A convenient form or construction of such switch consists of a cylinder 43 of insulating material mounted on the shaft 20 and metal springs 44 bearing on the cylinder. A metal band 45 is placed on the cylinder in line with the springs 44, said band extending around the cylinder except for a distance a little greater than the peripheral length of the knob 22 on the disk 3^a of the circuit breaker. The band 45 is so arranged that the springs 44 will not be in contact with the band when the knob 22 is in contact with the plate 23^a. The character of the waves can also be varied by connecting to the wire a condenser or capacity X or a self-inductance in the form of a coil Y. In lieu of the mechanism shown a series of siphon recorders may be employed as shown and described in Letters Patent No. 727,325.

As will be obvious the shaft 20 may be rotated preferably a number of times during the transmission of the shortest signal by any suitable means indicated at 20^a to successively make and break the primary circuit of the transmitting mechanism and at the corresponding period the receiving mechanism will be cut out by the break and make of the switch 44, 45. Obviously I am enabled by means of the above apparatus to signal by generating electrical impulses and to render the receiver unresponsive during the time of such generation and to receive impulses by rendering the receiver sensitive

during the time when the sending impulses are not being emitted and to cause such conditions to succeed each other so rapidly as practically to effect simultaneous transmission and reception of signals.

This application is a division of my prior application Ser. No. 53,441, filed March 29, 1901, (now Patent No. 777,014) which is a division of an earlier application Ser. No. 18,878, filed June 2, 1900, which latter application has resulted in Patent No. 727,325.

What I claim and desire to secure by Letters Patent is:

1. In the art of electric signaling, the method of simultaneously sending and receiving signals which comprises rendering the receiver at the sending station alternately responsive and unresponsive periodically while sending, the period of interruption being too short to interfere with the received signals and the receiver being responsive during the intervening non-sending intervals.

2. In wireless telegraphy, the method of simultaneously sending and receiving messages which comprises shifting the antenna alternately to association with the sending and receiving apparatus while sending, the periods of interruption of the receiving apparatus being too short to permit interference with signals composed of trains of separate groups of waves, and the signal being sent occupying the interval of interruption, substantially as described.

3. In the art of wireless signaling, the method which consists in transmitting electrical signals, each signal consisting of a train of rapidly succeeding groups of impulses, and rendering the receiver at the sending station unresponsive during the times of generation of such groups of impulses in the train, while leaving it responsive during the time intervals between the separate groups in a train.

4. In the art of wireless signaling, the method which consists in generating signals consisting each of a train of separate groups of electromagnetic waves, and cutting out the sensitive member of a receiving apparatus at the sending station during the time of actual generation of each group, and cutting the same in during the intervals between times of generation.

5. In the art of wireless signaling, the method which consists in generating a train of separated groups of electric impulses to form a signal, and rendering a receiver at the sending station insensitive during the times of such generation of individual groups in the train, and rendering said receiver sensitive during the intervening time intervals.

6. In the art of wireless signaling the method which consists in generating rapidly succeeding separate groups of electric im-

pulses, rendering a receiver at the sending station insensitive during the time of generation of each group and rendering said receiver sensitive during all the intervening times.

7. The method of simultaneously transmitting and receiving signals by electromagnetic waves which comprises sending a multiple group of waves of definite and high frequency, a train of such groups constituting a signal and altering the operative relation of a normally sensitive receiver to the antenna at the sending station to make it insensitive only during the actual time of sending each group of waves.

8. In wireless signaling the method of sending signals each consisting of a train of separated and rapidly succeeding groups of electric impulses and meantime altering the operative relation to the antenna of a receiver at the sending station so that it is in-

sensitive during the times of sending each group, and sensitive in the intervals between the multiple groups of impulses forming the signal.

9. In the art of wireless signaling, the method of simultaneously sending and receiving messages, which comprises transmitting signals composed of elements, each element comprising a number of groups of impulses, and each impulse comprising a number of high frequency oscillations, and rendering a receiver at the sending station unresponsive during the time of actual emission of each group of the elements, while leaving it responsive during the intervening time intervals.
